UNITED STATES PATENT OFFICE.

CHARLES F. SCOTT, OF PITTSBURGH, PENNSYLVANIA, ASSIGNOR TO WESTINGHOUSE LAMP COMPANY, A CORPORATION OF PENNSYLVANIA.

INCANDESCENT LAMP.

1,125,744.

Specification of Letters Patent. Patented Jan. 19, 1915.

Application filed May 19, 1909. Serial No. 497,052.

To all whom it may concern:

Be it known that I, CHARLES F. SCOTT, a citizen of the United States, and a resident of Pittsburgh, in the county of Allegheny and State of Pennsylvania, have invented 5 a new and useful Improvement in Incandescent Lamps, of which the following is a specification.

My invention relates to incandescent 10 lamps, and particularly to tubular lamps having straight filaments which extend from end to end thereof.

The object of the present invention is to provide a lamp of the character indicated 15 that shall embody simple and effective means for maintaining the filament thereof taut and out of engagement with the sides of the tubular casing.

It has been proposed to divide the straight 20 filaments of tubular incandescent lamps into sections and to interpose suitable tension devices between adjacent filament sections, and it has also been proposed to maintain the filaments out of engagement with the sides 25 of the tubular casings by means of supports that are fixedly mounted with respect to the said casings.

In the present application, it is proposed 30 to support the lamp filament out of engagement with the sides of the tubular casing by a means which is secured to the filament or to the tension device interposed between the sections thereof, or to any other suitable portion of the conductor system of the 35 lamp, the said supports being freely movable with respect to the casing. The tension devices are also so constructed as to permit them to assist in supporting the filament.

Figure 1 of the accompanying drawing is 40 a side view of a lamp constructed in accordance with the present invention, and Fig. 2 is a sectional view of the said lamp on the line II—II of Fig. 1. Fig. 3 illustrates a lamp embodying the preferred form of the 45 invention. Fig. 4 is a sectional view of the lamp shown in Fig. 3, and Fig. 5 is a side view of a portion of a lamp embodying another modification of the invention.

Arranged in end-to-end or series relation 50 within the tubular glass casing 1 of the lamp of Fig. 1, and extending between, and electrically connecting, the terminal members 2 that are mounted upon opposite ends of the tubular casing, are a plurality of sections 3,

4 and 5 of a filamentous material, such as 55 carbon or tungsten, that is adapted to become heated to incandescence upon the passage of an electric current therethrough. The filament sections 3, 4 and 5 are mechanically and electrically connected by means of 60 tension devices 6 and 7 that preferably consist of strips or wires of nickel, or other suitable material which retains its resiliency upon being heated, the said strips being reversely bent one or more times, substantially 65 as shown. The tension devices are adapted to maintain the filament taut, under all conditions, and to permit such expansion and contraction thereof as may result from heating and cooling. Of course, other forms of 70 tension devices may be employed instead of that shown.

In order to maintain the filament approximately central within the tubular casing and out of engagement with the sides thereof, 75 suitable supporting devices 8, such as three-legged or substantially Y-shaped devices illustrated, may be secured to the tension devices 6 and 7, or to the filament itself, as shown in connection with the middle section 80 4 of the filament, or they may be attached to the conductor system of the lamp at other desired locations, the said supporting members being freely movable within and with respect to the tubular casing 1 so as not to 85 interfere with the ready expansion and contraction of the filament. The attaching of the supporting devices to the conductor system is regarded as an important improvement for the reason that all of the parts contained within the tubular casing are secured 90 together and may be inserted therein simultaneously and without difficulty during the assembling of the lamp.

Since the tension devices 6 and 7 do not 95 possess a high degree of conductivity, it may be desirable, in some instances, to connect a copper or other suitable shunt 9 of high conductivity between the ends of adjacent filament sections.

In the lamp shown in Figs. 3 and 4, filament sections 11 and 12 are connected and maintained taut by means of a tension device 13 that serves the additional function of assisting in supporting the filament and 105 maintaining it out of engagement with the sides of the tubular casing 1. To this end, the device 13 consists, as before, of a strip or

wire composed of nickel or other material that retains its resiliency upon being heated, which strip is reversely bent a plurality of times and the reversely bent portions of which are disposed obliquely or at angles with respect to each other. The tension device may comprise three reversely bent portions as shown in the drawings, which is the preferable form, or it may comprise any other suitable number of such reversely bent portions.

In Fig. 5 is shown a portion of a lamp embodying a spring 14 of the same kind as that embodied in the lamp shown in Fig. 3, 15 a shunt 15 of high conductivity being employed for conducting the greater portion of the current between the filament sections. The ends of the shunt 15 are connected directly to the ends of the filament sections 20 and it is bent to provide hooked portions near its ends, with which the hooked ends of the spring 14 engage.

I claim as my invention:

1. An incandescent lamp comprising a 25 casing, a conductor extending therethrough, and one or more supporting members secured to the conductor and freely movable with respect to the casing.

2. An incandescent lamp comprising a 30 casing, a filament therein, separate resilient means in series with the filament, and a low resistance shunt connected around the resilient means.

3. In an incandescent lamp, the combination with a casing, and a system of conductors therein comprising a plurality of filament sections arranged end to end and resilient means interposed between adjacent filament sections, of means carried by the 40 system of conductors for assisting in supporting the filament.

4. In an incandescent lamp, the combination with a casing, and a system of conductors therein comprising a plurality of filament sections arranged end to end, and resilient means interposed between adjacent filament sections, of means carried by the system of conductors for assisting in supporting the filament, the said means being 50 freely movable within the casing.

5. An incandescent lamp comprising a casing, a plurality of filament sections arranged end to end therein, and resilient means interposed between adjacent filament sections having laterally projecting portions that assist in supporting the filament.

6. An incandescent lamp comprising a casing, a plurality of filament sections arranged end to end therein, resilient means interposed between adjacent filament sections, and means freely movable with respect to the casing to assist in supporting the filament.

7. In an incandescent lamp, the combination with a casing, and a filament therein, of

resilient means in series with the filament consisting of a spring bent to provide a plurality of doubled portions projecting laterally from the filament, the several doubled portions being angularly arranged with respect to each other. 70

8. An incandescent lamp having a filament comprising alined sections and provided with a support for the filament intermediate said sections, said support including a tension-producing member. 75

9. An incandescent lamp having a divided filament comprising alined sections and provided with a support for the filament intermediate its ends, said support including a 80 tension-producing member.

10. An incandescent lamp having a filament divided at an intermediate point and provided thereat with a tension-producing support, said filament being hooked to said support and the sections at each side of the intermediate point extending in opposite directions. 85

11. An incandescent lamp having a filament divided into a plurality of alined parts, 90 and provided with a spring support at the point of division between adjacent parts.

12. An incandescent lamp having a filament, comprising alined sections and provided with a flexible support for the filament intermediate its ends. 95

13. An incandescent lamp comprising a straight cylindrical tube, a filament axially contained therein, and a spring having an axial tension between its extremities to 100 which said filament is connected and which maintains the tension of the filament; said spring having a plurality of distinct opposing portions of substantially arcuate formation for contacting with the inner wall of 105 the cylindrical tube to position said filament in the tube axis.

14. An incandescent lamp comprising a tube, a filament contained therein and a spring having an axial tension between its 110 extremities, said filament being connected to one of said extremities and maintained taut by the spring tension, said spring having a plurality of distinct portions contacting with the inner wall of the tube at spaced intervals to position said filament in the tube

115

15. An incandescent lamp comprising a relatively long tube, a plurality of relatively short filaments axially disposed therein, a spring having the extremities thereof oppositely disposed, each of said extremities being secured to a filament end, portions of said spring being in contact with the inner wall of said tube, and said spring having an axial tension between its extremities, thereby 120 maintaining the respective filaments on either side thereof taut.

16. An incandescent lamp having a divided filament, and provided with a flexible support for the filament at the point of divi- 125

sion which support extends laterally to a section of the filament that incandesces.

17. An incandescent lamp comprising a casing, a plurality of filament sections arranged end to end therein, and resilient means interposed between adjacent filament sections having laterally projecting portions that assist in supporting the filament.

18. An incandescent lamp having a filament comprising incandescing sections arranged in tandem with a tension member

between the sections supported from the lamp tube in such a manner that it can move longitudinally relative to the tube.

In testimony whereof, I have hereunto 15 subscribed my name this 10th day of May, 1909.

CHARLES F. SCOTT.
